FUR BLOWING AND MIXING

John E. Kane, Danbury, Conn., assignor to The
Frank H. Lee Company, Danbury, Conn.

Application March 29, 1949, Serial No. 84,130

11 Claims. (Cl. 19—146)

1

This invention relates broadly to the mixing of fibers and to the manufacture of felt hats, and more in particular, it relates to blowing and mixing fur fibers or the like.

The term "fur" is used herein in its broadest sense as understood in the hat making art as including carotted fur fibers as well as other fibers which are mixed therewith.

An object of this invention is to provide for thoroughly dependable and uniform blowing and mixing of different fibers which may vary in type or kind, size and felting and other characteristics, with the action being such as to produce an improved result. A further object is to provide for the blowing and mixing of furs of different kinds so as to produce a homogeneous mixture which can be made into felt hats. A further object is to improve the procedure of handling fur in the manufacture of hats so as to avoid certain difficulties which have been encountered in the past. A still further object is to provide for the proper mixing of such fur with minimum handling and with minimum damage to the fur. Another object is to provide apparatus which will accomplish the above and yet which is simple and sturdy in construction and inexpensive to build, operate and maintain. These and other objects are in part obvious and in part pointed out below.

The invention accordingly consists in the features of construction, combinations of elements, arrangements of parts and in several steps and relation and order of each of the same to one or more of the others, all as will be illustratively described herein, and the scope of the application of which will be indicated in the following claims.

In the drawings in which is shown one illustrative embodiment of the invention:

Figure 1 is a somewhat schematic diagram representing a system for blowing and mixing fur which is a part of a system for making felt hats;

Figure 2 is an enlarged view of a portion of Figure 1 with parts broken away;

Figure 3 is a top plan view of the fur bin or box of Figures 1 and 2;

Figure 4 is an end elevation of the mechanism shown in Figure 2, as viewed from the right side thereof.

Figure 5 is an enlarged view with parts broken away of a portion of the feed mechanism as shown in Figure 2;

Figure 6 is an enlarged view with parts broken away of a portion of the feed mechanism, as shown in Figure 4; and,

Figure 7 is a schematic wiring diagram of the feed arrangement of Figures 2 to 6.

2

In the manufacture of felt hats it is desirable to use a mixture of different types of fur which vary widely in regard to tensile strength, felting characteristics, etc. For example, in mixing fur to make a specific type of felt hats, as many as twenty different types or kinds of fur may be selected some of which are extremely good in felting characteristics, and others of which act as "filler" or merely add body to the felt hat when completed. It is of course desirable to mix the different furs together with absolute uniformity so that the desirable characteristics of each kind of fur will be utilized and so that the felt produced will be of uniform characteristics. In the past the mixing of fur has involved considerable manual handling and it has been difficult at times to obtain a proper mixture of the fur without excessive working and without damage to the fur. Furthermore, the prior modes of mixing have involved a great lack of uniformity, and there has been loss of much valuable fur. It is among the objects of this invention to avoid these and similar difficulties which have been encountered in the past.

In the illustrative embodiment of the invention, the fur is handled in such a way as to insure absolutely uniformity in the mixing operation with the result that a uniform mixture is produced with minimum mixing action. Thus, the hats produced are of uniformly high quality, and the high-priced furs which are responsible for the production of a tight felt may be used sparingly without danger of producing inferior hats.

Referring particularly to Figure 1 of the drawings, there is shown at the left a conical mixer 2 which has an opening 4 into which relatively small quantities of various types of fur are fed. Mixer 2 separates and mixes the fibers of the fur and blows it entrained in a stream of air through a chute 6 upwardly into the top of a mixing chamber 8. The lower portion of chamber 8 is formed by a rectangular section 9 and the top is closed by a semi-cylindrical screen 10a enclosed by a cover 10b. An exhaust duct (not shown) is attached to the cover 10b to carry off air and dust. Screened windows 12 in the cover 10b permit access into and inspection of the chamber 8. Thus, chamber 8 is of rectangular horizontal section, and in its lower portion there is a large rectangular open-topped bin 14 which fits snugly within the chamber with its sides adjacent the side walls of chamber section 9. The arrangement is such that the fur from chute 6 loses its velocity in the top of the chamber and settles with uniform horizontal distribution into

bin 14. Chamber portion 9 has a pair of sliding side doors 11 which may be moved up for the removal of bin 14 and the bin is supported on casters 16 so that it may be moved easily. Therefore, after a sufficient quantity of fur has been deposited in the bin the conical mixer is stopped, the side doors 11 are raised and bin 14 is rolled from chamber 8.

It has been pointed out above that different kinds of fur are fed to the conical mixer in relatively small quantities. Therefore, the fur settles into the bin in strata which are fairly uniform, the bin then containing a stratified body of fur with the strata extending horizontally. During the next step in the operation the fur is removed from the end of the box in vertical strata or sections and it should be noted that each vertical stratum or section contains a section of each of the horizontal strata, i. e., a portion of each type of fur. The arrangement is such that thin vertical strata or sections are removed, and therefore very small quantities of the fur contain proportional quantities of each type of fur which is fed to the conical mixer.

As indicated above, bin 14 is mounted on casters 16 and has two side wall structures 20 and 22 (Figure 3), a left-hand fixed end wall 24, and a right-hand removable end wall 26. This right-hand end of the bin is referred to as the feed end of the bin, and wall 26 is loosely held at its side edges in two channels 28 so that it may be removed by sliding it upwardly and this exposes the end of the body of fur in the bin. Adjacent the fixed end wall 24 is a movable end wall 30 which is held in a vertical position but is adapted to move from the position shown to substantially the position normally occupied by the removable end wall 26.

The mounting structure for movable wall 30 includes two vertically spaced parallel shafts 34 (Figures 2 and 3) each of which extends through a sleeve 21 (Figure 2) fixed to the left-hand side of the movable wall 30. Each of the side wall structures 20 and 22 of the bin has a frame formed of angle bars and including two pair of spaced parallel angle bars which act as rails, there being an upper set of angle bars 23 and 25 (Figure 2) with an upper horizontal opening 31 therebetween, and a lower set of angle bars 27 and 29 with a lower identical opening 33 therebetween. The two ends of the upper shaft 34 extend through the two openings 31 and the two ends of the lower shaft 34 extend through the two openings 33, and mounted on each of the shafts within each of the openings is a roller 32 which is adapted to ride along between its two angle bars.

Extending between and mounted on the ends of the angle bars at each side of the bin is a vertical bar 35, and extending along each of these bars is a coil spring 36. The coil springs have integral loops at their ends which fit into grooves in shafts 34, and the springs are under tension so as to urge the shafts toward each other. Thus, the upper shaft 34 is pulled downwardly so that its rollers 32 ride on the lower rails 25, and the lower shaft 34 is urged upwardly so that its rollers ride on the upper rails 27. In this way wall 30 is firmly supported in its upright position, but the mounting is sufficiently resilient to provide for free movement of the wall without danger of becoming jammed due to canting.

Two or more bins 14 (Figure 1) are provided so that when one bin is filled with a body of fur it is removed from chamber 8 and is replaced with

another bin. In Figure 1 a second bin 14' is shown which has therein a stratified body of fur. This bin 14' is positioned with its end wall corresponding to the wall 26 (Figure 3) removed and with the body of fur at its right-hand feed end abutting the upwardly moving run of the feed apron 17 (Figures 1 and 2) of a feed mechanism 18. Feed mechanism 18 of this embodiment is of the type disclosed in U. S. Patent No. 2,362,315 of Paul Schultze, assigned to Doran Bros., Inc. of Danbury, Connecticut. This feed mechanism is here described sufficiently to fully understand the operation and reference may be had to that patent for a more detailed discussion thereof.

Feed mechanism 18 (Figures 1 and 2) has its apron 17 mounted at the top on a fixed roller 37 and at the bottom on an adjusting roller 39 (Figure 2) which is carried by an adjusting mechanism 41 having an eye bolt 43 and a nut 45 which may be turned to tighten or loosen the apron. The apron is driven through roller 37 by an electric motor 47 (Figure 4) mechanically connected thereto by a pair of pulleys and a belt 49. Apron 17 is formed by a plurality of slats 51 (Figure 2) mounted on a flexible sheet and each carrying a row of pins 53 which are in vertical alignment. Extending upwardly between the rows of pins on the upwardly moving run of apron 17 (Figures 2 and 4) are stationary rods 55 in which are mounted horizontal pins 57 (Figure 2) which project beyond the ends of the pins 53 carried by apron 17.

During its upward movement the pins on the apron gather fur to form an even layer, but the stationary pins 57 project into the body of fur so as to prevent a general movement of the fur upwardly. In this way the apron carries an even layer of fur upwardly without disturbing the main body of fur. Therefore, with bin 14' positioned in abutting relationship with the feed mechanism 18, and with movable wall 30 pressing the body of fur against the feed apron 17, the feed apron picks from the end wall of the body of fur successive thin vertical layers or sections of the body of fur which are transverse to the horizontal strata of the various types of fur. It has been pointed out that these horizontal strata of the various types of fur are substantially even and therefore, apron 17 picks up varying amounts of the different types of fur in substantially the proportions which they represent in the entire body of fur. Thus the apron delivers a continuous layer of fur which represents in cross section each of the types of fur in substantially the proportions desired in the final mixture.

The layer of fur is picked from apron 17 by a picker 40 (Figure 2), and the fur falls downwardly within a hood 42 onto an endless feed apron 44 (Figure 1). This produces a picking and further mixing action so that a loose, well-mixed layer of fur is deposited onto apron 44. At the right-hand end of apron 44 this layer of fur passes beneath a roller 46 to a pair of feed rollers which feed the fur to a cylindrical mixer 50. Mixer 50 rotates counterclockwise and picks the fur apart again and directs it entrained in a fast-moving stream of air upwardly through a chute 52 into a large mixing chamber 54 which has suction means to carry off the dust and air and windows 56 for inspection. The fur falls in an even layer onto an endless feed apron 58. At the right-hand end of apron 58 the fur passes beneath a roller 60 and thence between a pair of feed rollers to a second cylindrical mixer 64. Mixer 64 is similar to mixer 50 and picks, mixes

and blows the fur again and directs it entrained in a stream of air upwardly through a chute 66 into the top of a mixing chamber 68 which is formed by a structure similar to that of mixing chamber 8. From chamber 68, the fur descends in a uniform mixture into a rectangular bin 72 which is identical in every respect to bin 14. When bin 72 is full it is removed and replaced with another bin, and the uniform body of fur is ready for further blowing and depositing into bats to form hat bodies. The mechanism for removing the fur from bin 72 is not shown, but it is identical with feed mechanism 18.

As indicated above, movable wall 30 (Figure 3) is moved toward the feed end of the bin to move the stratified body of fur against the apron 17. The mechanism for moving wall 30 in this manner includes a pair of sprocket chains 14 and 16 which are attached at their left-hand ends respectively (Figure 2) to bars 35. The attachment between each chain and its bar is by a rectangular link 78 on the end of the chain which is received in a slot 80 in an ear 82 on the bar 35. The right-hand end of each of these chains (Figure 3) extends over a sprocket wheel 84 mounted on and keyed to a shaft 86 which is journaled in the frame of the feed mechanism 18. Also keyed to shaft 86 is a large gear wheel 88 which meshes with a small gear 90 (Figure 5) keyed to a shaft 92. Shaft 92 also has keyed to it a ratchet wheel 94, and is journaled in the frame of feed mechanism 18 (Figure 6).

Ratchet wheel 94 is adapted to be rotated counterclockwise (Figure 5) by an operating arm 96 which is journaled to rock free on shaft 92 and has a free end portion 98 overhanging the periphery of wheel 94. Portion 98 has a recess in which is rockably mounted a dog 100 which is urged toward ratchet wheel 94 by a leaf spring 102. The ratchet teeth of wheel 94 are also engaged by holding dog 104, which is pivoted by a bracket on the frame of the feed mechanism 18, and is gravity-urged toward the wheel. The ratchet teeth are cut as shown to permit only counterclockwise rotation of wheel 94 except when dog 104 is lifted. The extreme end of arm 96 is connected by a pin 106 to a piston rod 108 which is connected to a piston 111 of a fluid motor in the form of an air cylinder unit 110. Unit 110 has a cylinder 112 rockably mounted at its upper end by a bolt 114 to the frame of the machine, and air is supplied to cylinder 112 through a flexible hose 116 which is connected through a pipe 117 to a control valve 118. Air is supplied to valve 118 from a pipe 120 which has a pressure gauge 122 connected thereto. The air pressure in pipe 120 is maintained constant by a pressure-reduction valve 124 which is connected to a source of compressed air through a pipe 126.

Operating arm 96 carries a control arm 128 which has a substantially horizontal extension 130 (Figure 6). A substantially vertical arm 131 (Figures 5 and 6) extends from the end of the horizontal extension 130 and carries a pair of adjustable stud bolts 132 and 134. The end of bolt 132 swings into engagement with a normally open switch 136 (Figure 5) when the piston 111 of unit 110 and arm 96 move to the extreme upward position shown; and when the piston 111 moves down so that operating arm 96 swings counterclockwise from the position shown, control arm 128 is carried to the left and swings the end of bolt 134 into engagement with a normally closed interlock switch 138.

Unit 110 has a coil spring (not shown) which

urges its piston 111 toward the top of cylinder 112 and the piston is moved downwardly when air is supplied to the top of the cylinder through hose 116. The movement of the piston downwardly acts through piston rod 108 (Figure 5) to rotate operating arm 96 counterclockwise, and due to the engagement by dog 100, ratchet wheel 94 rotates counterclockwise along with the operating arm. Thus, when air under pressure is supplied to cylinder 112, unit 110 rotates ratchet wheel 94 counterclockwise through a predetermined arc. Then, when the air is released, the spring of unit 110 urges the piston 111 back up and carries the piston rod and arm 96 back to the positions shown. During the counterclockwise movement of ratchet wheel 94, dog 104 rides over the ratchet teeth and does not interfere with the free movement of the wheel; but during the return movement of the elements, dog 104 prevents ratchet wheel 94 from turning clockwise, and therefore, dog 100 rides over the ratchet teeth. Thus, by supplying air intermittently to cylinder 112 there is a progressive step-by-step feeding movement transmitted to ratchet wheel 94. This movement is in turn transmitted through shaft 92 and through gears 90 and 88 with a suitable reduction and reversal to shaft 86, which is thus rotated clockwise with a greatly reduced step-by-step movement. This clockwise movement is effective through sprocket wheel 84 to draw chains 14 and 16 (Figures 2 and 3) to the right, and, as pointed out above, this carries movable wall 30 to the right and presses the body of fur against apron 17. As apron 17 carries away successive vertical sections of the body of fur the remainder of the body of fur is moved toward the apron by this feeding action. As will be explained more fully below, this particular manner of feed has outstanding advantages.

The electrical circuit for the feed mechanism is shown schematically in Figure 7. Switches 136 and 138 are each connected at one side to a line 140, and the other line 142 is connected to one side of the valve-operating solenoid 144 and a relay solenoid 146. Solenoids 144 and 146 are each connected to the other side of switch 136 and the switch 148 of solenoid 146 is connected at one side to switch 138 and at the other side to the two solenoids. Thus, assuming that switch 136 is momentarily closed, a circuit is completed which energizes the solenoids with the result that valve 118 (Figure 5) is operated by solenoid 144, and switch 148 is closed by solenoid 146. The closing of switch 148 completes an interlock circuit from line 140 through switches 138 and 146 to the two solenoids, and therefore, the solenoids remain energized even though switch 136 opens. Thereafter, control arm 128 (Figures 5 and 7) moves to the left so that it engages and opens switch 138 and this opens the interlock circuit and de-energizes the solenoids.

During the feeding operation the engagement of bolt 132 (Figures 5 and 7) with switch 136 closes this switch and operates valve 118 to connect the constant pressure air supply of pipe 120 through hose 116 to cylinder 112; and interlock switch 148 maintains this connection after the engagement with switch 136 is discontinued while arm 128 swings counterclockwise. Then, when stud bolt 134 engages and open switch 138, valve 118 (Figure 5) immediately disconnects pipe 117 from the air supply of pipe 120, and connects pipe 117 to atmosphere. This exhausts the air and permits the spring of unit 110 to return the elements to the positions shown. Thus, a feed-

ing cycle is carried on wherein switch 136 is first closed so as to connect the air supply to cylinder 112 with the result that arm 96 moves downwardly and swings ratchet wheel 94 counterclockwise. This movement moves bolt 132 away from switch 136 and causes bolt 134 to engage switch 138, and this action disconnects the air supply and connects the cylinder to atmosphere so that the internal spring in the unit moves the piston 111 back up, and switch 136 is again closed and the cycle is restarted.

It has been pointed out that air reduction valve 124 maintains a constant pressure in pipe 120, and therefore, unit 110 exerts a constant driving force during the downward movement of the piston 111. The pressure in pipe 120 is so regulated that movable wall 30 (Figure 3) urges the body of fur to the right against apron 17 with a predetermined amount of force. The maximum rate of feed possible by operating unit 110 (Figure 5) continuously is in excess of the maximum rate necessary to hold the body of fur against apron 17. Therefore, during the time that the body of fur is first being moved up to the apron, unit 110 operates continuously with the step-by-step feed. However, when the body of fur is pushed against the feed apron with the desired amount of pressure, the force exerted by unit 110 is no longer sufficient to overcome the resistance to further movement. Therefore, the feeding operation is temporarily stopped with the air supply still being connected to cylinder 112, but with the back force preventing operating arm 96 from swinging counterclockwise to cause a further feeding movement. Thereafter as apron 17 carries fur from the body of fur, the force resisting the feeding movement is reduced, and the feeding operation is continued intermittently at frequent intervals.

It has been found that by this arrangement the apron carries away fur substantially evenly from the entire end wall of the body of fur. Bolts 132 and 134 are held in adjustment by lock nuts 152 and 154, respectively, (Figure 5) and the length of each feeding movement may be controlled by changing the adjustment of these bolts. As indicated above, the pressure with which the body of fur is urged against apron 17 may be regulated by changing the pressure of the air supply in pipe 120, and this is controlled by adjusting valve 124.

As many possible embodiments may be made of the mechanical features of the above invention and as the art herein described may be varied in various parts, all without departing from the scope of the invention, it is to be understood that all matter hereinabove set forth, or shown in the accompanying drawings is to be interpreted as illustrative and not in a limiting sense.

I claim:

1. In hat making apparatus for handling and mixing fur preparatory to the separation of the fur into quantities to form hat bodies, the combination of, a bin of substantially uniform horizontal section having vertical walls extending completely therearound with the wall at one side removable, first mixing means to deposit different types of fur in strata in said bin thereby to form a stratified body of fur, feeding mechanism to remove fur from said one side of the stratified body substantially in a zone extending transversely of the strata whereby fur is withdrawn from each stratum, second mixing means to mix the fur withdrawn from the body of fur

whereby fur of substantially uniform consistency is produced, and means to deposit the mixed fur for subsequent use.

2. Mechanism as described in claim 1 wherein said second mixing means includes a pair of spaced cylindrical mixers having a mixing chamber therebetween so related that the fur passes through one of said mixers and thence to said mixing chamber and to the other cylindrical mixer.

3. In apparatus of the character described, feeder means to remove fur from a body of fur, a cylinder, a piston mounted within said cylinder, a piston rod connected to said piston at one end of the cylinder, means mounting said cylinder at the opposite end thereof, a lever connected at one end to said piston rod and pivotably mounted at its other end, a ratchet wheel assembly mechanically associated with said pivotable lever so as to be driven with a step-by-step movement by the pivoting movement of said lever produced by reciprocation of said piston, and means to transmit the step-by-step movement of the ratchet wheel to produce relative advancing movement between the body of fur and said feeder means.

4. In apparatus for use in handling fur during the process of making felt hats or the like, the combination of, a substantially rectangular bin having two side wall structures and a removable end wall at the fur feeding end of the bin, an end wall at the end of the bin opposite said fur feeding end movable toward said fur feeding end, mounting means for said movable end wall including track means on said side walls, rollers guided by said track means, feeding mechanism for feeding fur in layer form from a body of fur in said bin including an apron having an upwardly moving vertical run operative to pick up fur in substantially vertical layers, and means to move said movable end wall toward the feeding end of the bin with a predetermined feeding action.

5. In apparatus of the character described, a bin having a movable wall, means for holding different furs in said bin in layer arrangement, means for removing said different furs from said bin in constant proportions, a fluid motor, a lever pivotably operative by said motor, a first switch having its contacts closed by said lever when said lever is in its starting position and thereby closing a circuit to energize said motor, a second switch opened by the pivoting movement of said lever and connected in said circuit to interrupt the energization of said circuit when opened, a ratchet wheel assembly rotatable by said lever during the energization of said motor and including a plurality of sprocket wheels, and sprocket chains mounted over said wheels and connected to said movable wall to provide a uniform movement of said wall towards said removing means during each energization of said motor.

6. In apparatus for mixing fur the combination of a bin of substantially rectangular form in horizontal section, means for depositing therein different types of fur in strata to form a stratified body thereof, said bin having a removable vertical wall at one side, feeder means to entrain and remove fur from the stratified body at said side transversely of the strata, and means to produce relative advancing movement between the body of fur and said feeder means.

7. In apparatus for mixing fur the combination of a bin of substantially rectangular form

in horizontal section, means for depositing therein different types of fur in strata to form a stratified body thereof, feeder means to entrain and remove fur from the stratified body at one side thereof transversely of the strata, said bin having a movable opposite side wall and means for progressively advancing said opposite wall and maintaining it in engagement with said stratified body and correspondingly progressively advancing the body into engagement with said feeder means.

8. In apparatus for mixing fur the combination of a bin of substantially rectangular form in horizontal section, means for depositing therein different types of fur in strata to form a stratified body thereof, said bin having a removable vertical wall at a front side thereof, feeder means operable substantially parallel to said removable wall to entrain and remove fur from the stratified body at said front side transversely of the strata, said bin having a movable rear wall opposite to said front wall and means for progressively advancing said rear wall and correspondingly maintaining it in engagement with the rear face of said stratified body and progressively advancing the body toward said feeder means.

9. In apparatus for mixing fur the combination of a bin for a body of fur provided with means for exposing one side of the body of fur, feeder means adapted to be positioned at said side and arranged to entrain and remove fur progressively from said side, said bin having a rear wall adapted to be traversed forwardly through said bin, and power means for forwardly feeding said wall and maintaining it in engagement with the rear face of said body of fur to support continuously said rear face and to feed the body of fur forward into engagement with said feeder means.

10. In apparatus for mixing fur the combination of a bin for a body of fur provided with means for exposing one side of the body of fur, feeder means adapted to be positioned at said side and arranged to entrain and remove fur

progressively from said side, and means to advance the body of fur toward said feeder means, said advancing means including a movable member arranged to engage the body of fur at the side opposite to said feeder means, and power means for urging said member forward with a substantially constant predetermined pressure thereby to exert a substantially constant pressure between said body of fur and the feeder means.

11. In apparatus of the character described, wall means forming a compartment for a body of fur so arranged that one side of the body of fur may be exposed, fur-feeding mechanism positioned against said exposed side of the body of fur and operative to pick fur substantially evenly from the side wall, and means to urge together the body of fur and said fur-feeding mechanism, said means including means to engage the body of fur at the side opposite said fur-feeding mechanism and power means to exert a predetermined pressure therebetween wherein said power means includes a fluid cylinder operative to exert a driving force dependent upon the pressure of the fluid supplied thereto, and means to supply fluid having a predetermined maximum pressure to said fluid cylinder.
